UNITED STATES PATENT OFFICE.

WILLIAM GUYTON, OF AVALON, PENNSYLVANIA, ASSIGNOR OF ONE-HALF TO ROBERT STINSON, OF PITTSBURG, PENNSYLVANIA.

FLUSHING APPARATUS.

976,870.

Specification of Letters Patent. Patented Nov. 29, 1910.

Application filed March 31, 1910. Serial No. 552,607.

REINHOLD

To all whom it may concern:

Be it known that I, WILLIAM GUYTON, a citizen of the United States of America, residing at Avalon, in the county of Allegheny and State of Pennsylvania, have invented certain new and useful Improvements in Flushing Apparatus, of which the following is a specification, reference being had therein to the accompanying drawing.

10 This invention relates to a flushing apparatus for the bowls and hoppers of water closets, and the primary object of my invention is to provide a tank with an automatic valve adapted to be intermittently actuated 15 to release a predetermined quantity of water to flush the bowl or hopper.

Another object of this invention is to provide a flushing apparatus that can be advantageously used in connection with out-20 door closets and by being regulated it will prevent the water of the flushing tank from freezing by from time to time releasing predetermined quantities of water which will also prevent the water within a hopper or 25 bowl from freezing.

A further object of this invention is to provide a flushing tank with a primary and a secondary float, the former controlling the 30 operation of the latter in such a manner that the exhaust of water from a tank will be controlled by the secondary float.

A still further object of this invention is to accomplish the above results by an apparatus that is simple, durable, inexpensive to 35 manufacture, applicable to various types of tanks, free from injury by ordinary use, and efficient as a flushing apparatus for various kinds of receptacles.

With the above and such other objects in 40 view as may hereinafter appear as the invention is better understood, the same consists of the novel construction, combination and arrangement of parts to be hereinafter specifically described and then claimed.

45 Reference will now be had to the drawing forming a part of this specification, wherein:

Figure 1 is a vertical longitudinal sectional view of a tank provided with my apparatus, and Fig. 2 is a similar view showing a portion of the apparatus in section.

In the accompanying drawings the reference numeral 1 denotes a tank made of porcelain, glass, or other suitable material not 55 susceptible to any chemical action by the

contents thereof. The bottom 2 of the tank is provided with an outlet opening 3 and an inlet opening 4, and extending through the former is a coupling pipe 5 having the lower end thereof threaded, as at 6, to receive 60 an outlet pipe (not shown), while the upper end of the coupling pipe 5 is flared or flanged to form a valve seat 7. Communicating with the coupling pipe 5 is the angular end 8 of a vertical overflow pipe 9 having the upper end thereof in proximity to the upper 65 edges of the tank.

Detachably mounted upon the upper end of the overflow pipe 9 is a bracket 10, one end of the bracket being bifurcated to form 70 a clamp 11 adapted to embrace the upper end of the pipe 9 and frictionally engage the same through the medium of a set screw 12, while the opposite end of said bracket is bifurcated, as at 13, and provided with a 75 pivot pin 14. The bracket 10 intermediate the ends thereof is provided with an opening 15 having the walls thereof threaded to receive the upper threaded end of a tube 16, the lower end of said tube being screwed in 80 an opening 17 provided therefor in a support 18. The support 18 has one end thereof clamped to the pipe 9, as at 19, similar to the clamped end of the bracket 10, while the opposite end of the support 18 is provided with a leg 20 secured to the bottom 85 2 of the tank 1 by a screw 21 or other fastening means.

The upper threaded end of the tube 16 is provided with a jam nut 22 adapted to engage the lower side of the bracket 10, and the upper end of said tube is provided with vertical oppositely-disposed slots 23 for a transverse pin 24 carried by a stem 25 extending through the tube 16. The upper 95 end of the stem 25 is loosely mounted in a plug 26 mounted in the upper end of the tube 16, while the lower end of the stem is provided with a flexible valve 27 adapted to engage the seat 7 of the coupling pipe 5, 100 said valve being of a conventional form made of rubber or other flexible and yieldable material.

Slidably mounted upon the tube 16 is a hollow cylindrical float 28 having a central 105 vertical sleeve 29 adapted to receive the tube 16, said float having the upper end thereof beveled, as at 30, while the lower end of said float is adapted to normally rest upon the support 18.

Supported by the pivot pin 14 is an angularly shaped locking lever 31 having the lower end thereof bifurcated and provided with an anti-friction revoluble wheel 32 adapted to engage the beveled surface of the float 28. The opposite end of the lever 31 is provided with an opening 33 for a vertical rod 34 loosely mounted in an opening 35 provided therefor in the support 18 adjacent to the leg thereof. The upper end of the rod 34 is held in engagement with the lever 31 by nuts 35 having semi-spherical bearing surfaces 36 engaging the upper and under sides of the lever 31. Movable mounted upon the rod 34 is a cylindrical hollow float 37 having a central vertical sleeve 38 adapted to receive said rod, said float normally resting upon the support 18.

In the inlet opening 4 of the tank is mounted a coupling piece 39 to which is adapted to be connected a water supply pipe (not shown) adapted to have a suitable regulating valve for controlling the flow of water into the tank 1.

The operation of the flushing apparatus depends on the flow of water into the tank 1, and I will assume that the flow has been regulated to operate the flushing apparatus every few minutes. With the water entering the tank the level of the water will gradually rise and elevate the float 37 upon the rod 34, until the upper end of the float 37 engages the lowermost nut 35 at the upper end of the rod 34. The lever 31 will then be moved and the wheel 32 thereof carried out of engagement with the upper end of the float 28. The buoyancy of the float will then cause the same to rise and impinge the transverse pin 24, raise this pin and the stem 25 and thereby unseating the valve 27. As the water flows through the coupling pipe 5 the float 28 will descend, also the float 37, and immediately upon the float 28 contacting with the support 18, the wheel 32 will be swung inwardly to engage the upper end of said float. This is accomplished by the outer end of the lever 31, the nuts 35 and the rod 34 being of a greater weight than the short arm of the lever. When the float 28 returns to its normal position the valve 27 is closed, and as water again accumulates in the tank, the float 37 will be carried upwardly and the same operation performed as just described.

From the foregoing it will be observed that I have devised a novel flushing mechanism that can be intermittently operated to flush the bowl or hopper and the operation of the mechanism controlled by simply reg-

ulating the flow of water to the flushing tank.

While in the drawings there is illustrated a preferred embodiment of the invention, it is to be understood that the structural elements thereof can be varied or changed, as to the size, shape and manner of assemblage without departing from the spirit of the invention.

What I claim, is:

1. In a flushing apparatus, a tank having a water inlet and a water outlet, an overflow pipe connecting with said water outlet, a valve adapted to normally close said water outlet, a support arranged within said tank and connecting with said overflow pipe, a secondary float normally resting upon said support and adapted to elevate said valve, a bracket carried by the upper end of said overflow pipe, a lever pivotally mounted at the outer end of said bracket and adapted to normally hold said secondary float upon said support, a rod carried by said lever and extending through said support, and a primary float movably mounted upon said rod and adapted to be elevated by the contents of said tank to move said lever and release the secondary float.

2. In a flushing apparatus, a tank having a water inlet and a water outlet, an overflow pipe in communication with said water outlet, a support arranged within said tank, a bracket carried by the upper end of said overflow pipe, a slotted tube arranged between said support and said bracket, a valve stem movably mounted in said tube, a valve carried by the lower end of said stem and adapted to normally close said water outlet, a transverse pin carried by said stem and protruding through the slots of said tube, a secondary float movably mounted upon said tube and adapted to engage said pin and elevate said valve, a lever pivotally supported by said bracket and adapted to normally retain said secondary float upon said support, a rod connected to the outer end of said lever and extending downwardly through said support, and a primary float movably mounted upon said rod and adapted to be elevated by the contents of said tank to move said lever and release said secondary float.

In testimony whereof I affix my signature in the presence of two witnesses.

WILLIAM GUYTON.
